UNITED STATES PATENT OFFICE.

WINTHROP D. BAKER, OF ABINGTON, MASSACHUSETTS, ASSIGNOR TO REECE SHOE MACHINERY COMPANY, OF BOSTON, MASSACHUSETTS, A CORPORATION OF MAINE.

MACHINE FOR CEMENTING BOOTS AND SHOES.

1,216,539.

Specification of Letters Patent. Patented Feb. 20, 1917.

Application filed March 22, 1916. Serial No. 86,314.

To all whom it may concern:

Be it known that I, WINTHROP D. BAKER, a citizen of the United States of America, and a resident of Abington, in the county of 5 Plymouth and State of Massachusetts, have invented certain new and useful Improvements in Machines for Cementing Boots and Shoes, of which the following is a specification.

- 10 This invention relates to devices for applying cementitious fluid material to the portions of a shoe requiring such treatment during the manufacture thereof.
- 15 The object of the invention is to supply a device that is simple in construction and rapid in its operation and that will supply cementitious fluid to the parts and only to the parts where it is required; as for instance, in the so-called McKay shoe wherein 20 the sole is first channeled around its edge and the lip of the channel turned back upon the sole, and the sole and the upper then united by stitching, the stitches being placed in the channel and the lip thereof must then 25 be replaced to cover the otherwise exposed stitches.

In order to insure the retention of the lip in its place, the cementitious fluid is used, and is generally applied by hand in a slow 30 and oftentimes unsatisfactory manner. The object of this invention is to so place and control the operation of the fluid distributing devices as to enable the operator to evenly, accurately, and speedily with one movement 35 of the shoe in one direction, complete the operation of applying the cementitious fluid.

It is obvious that this device may be used with equally good results on welt shoes or the so-called "stitch down", or in any work 40 wherein the cementitious fluid is required to be applied to the work adjacent the edge thereof, whether of regular or irregular contour.

Other objects of this invention will be 45 further pointed out in the specification and the claims hereunto annexed.

Of the drawings:

Figure 1 is a left side elevation partially broken away, with a shoe in position to be 50 operated upon.

Fig. 2 is a part plan view of the device below the line 2-2 on Fig. 1.

Fig. 3 is a front elevation partially

broken away to better illustrate the application of the device.

Fig. 4 is a vertical transverse section 55 through one of the distributers to be described.

Similar characters designate like parts throughout the several figures of the drawings.

Referring to the drawings, 10 is a suitable standard to which is rigidly secured the reservoir or container 11 adapted to receive cementitious fluid, said container being of 65 such construction as to permit the material therein to be heated to a given temperature as by means of a steam jacket 12. Below the container 11 and rigidly secured to the standard 10 is an overhanging arm or 70 bracket 13 to which are pivoted at 14 the arms 15 under the control of springs 16.

Adjustably attached to the arms 15 near the ends thereof are the revoluble brushes or distributers 17 mounted in brackets 18 adjustably secured to the arms 15 by means of screws 20. The brushes 17 (see Fig. 4) have a cylindrical body portion or holder 21 shown as set screwed to a revoluble sleeve 22 depending from the sheave 23, said sleeve 22 80 having a running fit in the bracket 18, the sheaves 23 being driven preferably in the direction of the arrows *a* on Fig. 2 by the straight and cross belts 24-25 respectively, and the belt 26 (see also Fig. 1).

The sheave 23 and sleeve 22 are bored as at 27 to loosely receive a centrally bored stem 28 provided intermediate its ends with a valve 29 adapted to be closed when the brushes are to be removed or replaced to 90 thereby prevent the escape of the fluid.

The brush proper is so constructed as to leave an opening through its center as at 30 which is in register with the bore of the stem 28, said opening providing a passage 95 for the fluid to reach the surface of the work where it will be evenly distributed by the relative bodily movement of the brushes 20 and work, and the rotary movement of the said brushes.

The container 11 has fitted to it at its under side a slide valve 31 having a Y connection 32 to which the flexible conduits 33 are attached, the other ends of which are attached to the stem 28.

The arms or carriers 15 have pivoted to

them slidably the revoluble guide disks 34 adapted to engage the shoe between them at a point between the sole and the upper or the welt and the upper, as the case may be, 5 said arms 15 being provided with abutment stops 19 (see Fig. 2). Said disks 34 are so situated below the brushes 17 as to act as a support for the work, and of such a distance as to hold the work in operative contact with the brushes 17.

10 If, however, greater pressure is required on the work, the guide disks 34 being slidably mounted on their pivots 35 will permit of the work being pressed toward the 15 brushes 17, to the satisfaction of the operator.

As it is desirable to eliminate waste of the cementitious fluid between operations, a control device is provided that starts the flow of fluid when the work is presented to the 20 machine, and when the particular operation is completed the said control automatically stops the flow of fluid to the brushes 17. To thus control the flow of the fluid the 25 valve 31 is provided with a spring pressed stem having the collars 36 fast thereon, and between which the bifurcated end of a lever 37 is positioned, said lever 37 being pivoted at 38 to an extension of the bracket 13 (see 30 Fig. 1) and at its lower end has mounted thereon the roll 39, the normal position of which is indicated by dotted lines (Fig. 1), that being the position the roll will assume, and the valve 31 will be closed, due to the 35 absence of work beneath the roll and the expansion of the spring encircling the stem of the valve 31.

When work is presented to the machine, it must first contact with the roll 39 before 40 reaching the guide disks 34 and brushes 17, and in the placing thereof the lever 37 will be tilted so as to move the valve stem against the action of its spring, and thereby open the valve 31 for the fluid to pass to the 45 brushes 17.

The shoe shown in section in Fig. 3 is of the well-known McKay type wherein a channel 40 is cut around the sole of the shoe and the lip 41 turned back upon the sole so 50 that the stitches 42 uniting the sole and upper may be placed in the channel.

As this lip must again be returned to its original position upon the completion of the stitching, it is necessary to coat the channel 55 and the lip with a cementitious material or fluid, and this has heretofore been done by hand in a time wasting and slipshod manner, to the detriment of the work.

It is obvious that with a machine of this 60 description, shoes of the McKay, welt, or stitchdown type may be very rapidly coated at the desired place, as in this instance a narrow path or coating around the entire sole, with but one movement of the shoe in 65 a direction toward the machine. In other

words, a back and forth motion of the shoe would not be necessary to accomplish the desired result, although it is not prohibited. It is also obvious that the operator is not obliged to use both hands, as it is not necessary to turn the shoe to effect the proper operation of the coating devices.

It is also obvious that various changes and arrangements might be made amounting to mechanical skill without departing from the spirit and scope of this invention. It will be understood that in place of the guide disks 34, other means may be employed, such, for instance, as a form corresponding to the shape of the shoe with suitable followers to control the movement of the distributors.

It is believed that the many advantages of this invention will be fully understood from the foregoing description.

Having thus described my invention, I claim:

1. In a device of the class described, a plurality of revoluble fluid distributors the axes of which are arranged perpendicularly to the work to be operated upon; carriers for said distributors adapted to be swung toward or from each other; means to rotate said distributors; means to swing said distributors toward each other; and means governed by the work to separate said distributors.

2. In a device of the class described, a plurality of fluid distributing devices; yieldingly mounted supports therefor; and guide members adapted to contact with the work to control the position of said distributing devices.

3. In a device of the class described, a plurality of movable arms; fluid distributors 105 revolvably and adjustably mounted thereon; means to supply said distributors with cementitious material; and guide members adjacent said distributors.

4. In a device of the class described, a 110 plurality of yieldingly mounted carriers; fluid distributors revolvably, adjustably and detachably mounted thereon; shiftable guide members adjacent said distributors; a container; flexible conduits connecting said distributors and container; a valve in said container; and a lever adapted to contact with the work and operate said valve.

5. In a device of the class described, pivotally mounted arms; fluid distributors 120 mounted at the ends thereof; guide disks mounted on said arms adjacent to said distributors and adapted to contact with the work and follow the contour thereof during the progress of the work.

6. In a device of the class described, a plurality of yieldingly mounted carriers; fluid distributors adjustably mounted thereon; and shiftable guide members revolvably mounted on said carriers, and adapted to 130

contact with the work to thereby control the operative position of the said distributors.

7. In a device of the class described, a pair of yieldingly mounted pivoted arms; a fluid distributor detachably mounted at the ends thereof; guide disks adapted to contact with the sides of a shoe to control the operative position of the said distributors and to support the shoe; and means to supply cementitious fluid to the said distributors when the shoe is presented to the device.
8. In a device of the class described, a reservoir for cementitious material; a pair of laterally swinging arms; means to normally hold said arms together; a brush mounted on the end of each arm; flexible conduits connecting said reservoir and said brushes; valves in said conduits; a revoluble disk slidably mounted on a pivot at the end of each arm adjacent to said brushes; and an abutment stop to limit the movement of the arms in one direction.
9. In a device of the class described, a reservoir for cementitious material; a pair

of laterally swinging arms; means to normally hold said arms together; a brush rotatably mounted on one end of each arm; means to rotate said brushes; and rotatable guide disks adapted to be shifted in the direction of rotation of their axes and so mounted as to cause a separation of said swinging arms and attached brushes when a shoe is passed between them.

10. In a device of the class described, distributing means; work contact devices; and means intermediate said distributing means and said contact devices whereby said distributing means will follow the contour of the work to be operated upon.

11. In a device of the class described, distributing means; guiding means; and means intermediate said distributing means and said guiding means whereby said distributing means will be compelled to follow the contour of the work to be operated upon.

Signed by me at Boston, Mass., this 17th day of March, 1916.

WINTHROP D. BAKER.
